(57) **CLAIM**

The ornamental design for a cup with lid as shown and described.

DESCRIPTION

FIG. 1 is a top, front, right, exploded perspective view of the claimed design for a cup with lid;

FIG. 2 is a top, front, right perspective view thereof;

FIG. 3 is a front view thereof;

FIG. 4 is a back view thereof;

FIG. 5 is a right view thereof;

FIG. 6 is a left view thereof; and,

FIG. 7 is a top view thereof.

The broken lines immediately adjacent to the shaded area depict boundaries of the claimed design and form no part thereof. The broken lines showing the remainder of the cup with lid depict environmental structure and form no part of the claimed design. The bracket and break line indicia, and distance between the break lines, represent indeterminate length and form no part of the claimed design.
